PRINTING TELEGRAPH SELECTOR

Walter J. Zenner, Des Plaines, Ill., assignor to
 Teletype Corporation, Chicago, Ill., a corpora-
 tion of Delaware

Application March 19, 1949, Serial No. 82,391

27 Claims. (Cl. 178—33)

1

The present invention pertains to printing telegraph apparatus and more particularly to high speed selector mechanisms for controlling the operation of such apparatus.

The primary object of the invention is to provide a highly sensitive selector mechanism capable of operating at high speeds to control effectively the setting of mechanical elements.

Another object of the invention is to accelerate selecting operations by providing the selector magnet with a lightweight armature cooperable with a minimum number of sensing elements.

A further object of the invention is to provide a selector mechanism having a single sensing element cooperable with the armature of the selector magnet to control the selective functioning of a plurality of selectors.

Another object of the invention is to provide a pair of interlocking means associated with the selector magnet armature to lock said armature in marking or spacing position during the respective signal impulse interval under the control of a pair of control cams.

Briefly, the selector mechanism according to the present invention comprises a group of signal magnet controlled members which are successively and selectively operated positively in accordance with the nature of the received signal impulses. The selectable members are effective under predetermined selecting conditions to operate a corresponding group of slidable actuators, which function through oscillatable instrumentalities to condition interponents for cooperation selectively with a constantly operating pair of scissor bars to which motion is imparted by a toggle drive means.

A better understanding of the invention may be had by reference to the following detailed description when considered in conjunction with the accompanying drawing, wherein,

Fig. 1 is a perspective representation of the selector mechanism according to the present invention;

Fig. 2 is a fragmental rear perspective view of a portion of the selector mechanism shown in Fig. 1;

Fig. 3 is a cross sectional view of the selector mechanism through the selector cam shaft; and

Fig. 4 is a timing chart showing the relative time of operation of the various cams in the apparatus, and illustrating the time in which the various functional operations are performed.

Referring now to the drawings wherein like reference characters designate the same parts throughout the several views, particular reference

2

being had to Fig. 1, the numeric 11 designates the selector magnet which is considered as suitably and appropriately supported by means (not shown) in the telegraph printer apparatus. Associated with the selector magnet 11 is an armature member 12 pivotally mounted on a pivot shaft 13. Armature member 12 is normally biased counterclockwise (as viewed in Fig. 1) by a spring 14.

An important feature of the present invention resides in the provision of a very lightweight armature, thus reducing to a minimum the load on the selector magnet 11. In the present embodiment, the armature 12, in order to effect selective operations need only cooperate with a single sensing lever or sensor 15. However, in one form of the invention, a pair of sensing levers or sensors 15 and 16 provide an interlocking means to lock the armature 12 in marking or spacing position during the respective signal impulse interval under the control of a pair of control cams 17 and 18. Thus, the mass of the armature is reduced, since it need not span all of the selector levers, as will presently appear, but only the sensor 15 or the sensing levers 15 and 16, as the case may be.

Having reference to Fig. 3, it is observed that the sensing levers or sensors 15 and 16 are provided with oppositely disposed confronting shoulder portions 19 and 21, respectively, which cooperate with the narrow extremity of the armature 12. When the armature 12 is in the marking position (solid line position in Fig. 3), the sensor 15 will be urged by its spring 22, when permitted by its cam 17, to position table portion 23 underneath the outer end portion of armature 12 so that the armature 12 becomes locked between the shouldered portion 21 of lever 16 and table portion 23 of lever 15. On the other hand, when the armature 12 is in the spacing position (dotted line position in Fig. 3), the sensor 16 will be urged by its spring 24, when permitted by its cam 18, to position its surface 25 above the outer end portion of armature 12 so that the armature 12 becomes locked between the shouldered portion 19 of sensor 15 and surface 25 of sensor 16.

The sensor control cams 17 and 18 are carried on a sleeve 26 mounted on a shaft 27. Also carried on the sleeve 26 are a start cam 28, five selector cams 31 to 35, inclusive, and a bail operating cam 36. A stop disc 37 is also carried on the sleeve 26. The aforementioned cams and stop disc are angularly arranged on the sleeve 26 in a manner to effect, in predetermined timed relation, the operation of the follower elements

or selectors 41 to 45 in response to received code signal impulses. The cam notches 133 on the selector cams 31 to 35 are arranged in a helical manner, as exemplified by the diagram shown in Fig. 4, and the cam sleeve 26 is rotated at a speed commensurate with the speed of code impulsion.

In accordance with well known practice, the normal condition of the signal line 47 is a marking condition; that is, current on the line. In this condition, the selector magnet 11 is normally energized and its lightweight armature 12 is pulled up, in opposition to spring 14, as indicated in Fig. 1 with its extremity engaging the shoulder 21 of the sensing lever 16. Cooperating with the lever 16 is a laterally extending portion 48 of the vertical arm 49 of a stop bail 51 mounted pivotally on an appropriately positioned shaft 52. The horizontal arm 53 of the bail 51 is provided at its extremity with a suitably conformed stop portion 54 which cooperates with the stop projection 55 on the stop disc 37. The extremity 56 of the vertical arm 49 of bail 51 confronts a notch 57 formed in the disc 28 in the stop position of the cam sleeve 26 and the stop portion 54 engages the stop projection 55.

The stop position of the cam sleeve 26, the control cam 17 presents a high portion to its cam follower 58 on the sensing lever 15 so as to hold the shoulder 19 out of the path of the extremity of the armature 12. At the same time, the control cam 18 presents a low portion thereof to the cam follower 59 on its associated sensing lever 16. In this relative position of cams 17 and 18 the levers 15 and 16 are held in the position shown in Fig. 3 during the stop interval. Now, in response to a start signal impulse, which is of spacing (or no current) nature, the selector magnet 11 will become de-energized, and the spring 14 will urge the armature 12 away from the magnet core to the dotted position shown in Fig. 3. In this condition, the extremity of armature 12 is disengaged from shoulder 21 thus permitting the lever 16 to respond to the pull of its spring 24 due to the presence of the cam notch 61 of cam 17 in front of the follower 59 of lever 16.

Sensing lever 16 will thus rotate a predetermined amount in a clockwise direction (as viewed in Figs. 1 and 3), thereby permitting the bail 51 to also rotate a corresponding amount in the same direction due to the fact that the arm 49 can fall into the notch 57 of disc 28 and the portion 48 can follow the movement of the lever 16. The hole 20 is provided to eliminate interference between the leading end of lever 16 and the armature when the armature 12 is locked by shoulder 23. The bail 51 is thus rotated clockwise (Fig. 1) a sufficient amount to release the end 54 from the stop projection 55 to permit the cam sleeve 26 to rotate. The disc 28 will, after a predetermined amount of rotation sufficient to permit the stop lug 55 to escape end 54, thereafter function to hold the bail 51 in its counterclockwise position to prevent vibration thereof during the signaling period and until the stop period is reached whereat the lever 16 will again become blocked by the armature 12, as hereinbefore described, and be effective to hold the bail 51 in its counterclockwise position to stop the rotation of disc 37 after the completion of one cycle of rotation.

Having reference to Fig. 3, it is observed that the cams 17 and 18 are provided with cam projections 62 to cause the levers 15 and 16 to vibrate in unison with code impulsion. The apices 62 engage the followers 58 and 59 substantially dur-

ing the transition time between code signal impulses. Then when the armature 12 assumes its attracted or retracted position a hollow 63 of the cams 17 and 18 is presented to the cam followers 58 and 59 to permit clockwise movement of sensing levers 15 and 16, in the manner previously described. Briefly, for a marking or current condition the sensing lever 16 is blocked, and the armature 12 is locked between the shoulder 21 and the table 23. For a spacing or no current condition the sensing lever 15 is blocked, and the armature 12 is locked between the shoulder 19 and the surface 25.

The sensing lever 15 is provided at its upper end with a pair of arms 64 projecting from each side thereof sufficiently to span the upper ends of the selector levers or follower elements 41 to 45, inclusive, which are supported pivotally on a pivot shaft 65. Suitable spacer sleeves 66 are provided to properly space the follower elements 41 to 45, which are normally biased clockwise (as viewed in Fig. 1) by individual springs 67 to tend to cooperate with the selector cams 31 to 35 associated therewith through the follower portions 68.

Each of the follower elements 41 to 45 is conformed like the follower element 42 shown in Fig. 1. The remaining follower elements have been broken away for clarity. The followers 41 to 45, exemplified by follower 42, are each provided with a bearing surface 69 by means of which they normally tend to rest against the arms 64. The followers 41 to 45 are each provided with a jaw-like extremity and into the opening 71 of which one end of a slidable actuator or interponent 72 is adapted to operate. The jaw or opening 71 is provided with a stepped portion 73 for a purpose hereinafter described. The other end of the interponent 72 rests upon a support 74 fixed to the main apparatus and is provided with a depending portion 75. A spring 76 normally urges the interponent 72 rightwardly (as viewed in Fig. 1) so that the depending portion 75 normally bears against the support 74.

Cooperatively associated with the interponents 72 is a corresponding group of transfer instrumentalities or members 81 to 85, inclusive, mounted pivotally on a pivot shaft 86. Suitable spacing sleeves 87 maintain the members 81 to 85 in proper space relation. Each member 81 to 85 is provided with a pair of vertically directed arms 88 and 89. Arm 89 cooperates with the associated interponent 72, while the arm 88 cooperates with the depending stem portion 90 of one of a corresponding group of Y-levers 91 to 95, inclusive, mounted pivotally on a pivot shaft 96. A spring 97 is extended between the stem 90 of a Y-lever 91 to 95 and a spring post 98 integral with the arm 88 of its associated member 81 to 85. In the drawings (Fig. 1), the spring 97 is shown extended between Y-lever 92 and its associated transfer member 82. The spring 97 tends to contract and to force the Y-lever 92 and the member 82 into a dead center relation on the vertical center line between shafts 86 and 96. However, the right-hand edges of members 81 to 85 (exemplified by member 82 in Fig. 1) adjacent the arms 89 rest against the support 74. These members 81 to 85 operate in comb slots in the support 74. Therefore, the spring 97 is normally extended a predetermined extent, and in its effort to contract, it urges member 82 in a clockwise direction against the support 74. Then, when member 82 is actuated in a counterclock-

5

wise direction (as viewed in Fig. 1) as will hereinafter appear, the spring 97 will be further stretched or extended while causing the Y-lever 82 to rotate clockwise about shaft 96 with the lower end of stem 90 fulcruming about the upper inner edge of arm 88. Thus, the member 82 and its associated Y-lever 92 approach but do not attain a dead center relationship, thereby assuring normal contractual relationship between stem 90 and arm 88, as well as abutting relationship between member 82 and the stop 74.

The vertically directed arms or bifurcations of the Y-levers 91 to 95 terminate in inwardly directed confronting portions 99 and 100. For example, between the confronting portions 99 and 100 of lever 92, a slide element 101 is operable. Slide 101 is one of a group of push-pull elements or slides 101 to 105, inclusive, corresponding to the group of Y-levers 91 to 95, inclusive. Each of the slides 101 to 105 is provided with a pair of oppositely disposed offsets or shoulders 106 and 107 which cooperate with a pair of blades 108 and 109, respectively, of a scissors type operating mechanism, indicated generally by the numeric 111. The blades 108 and 109 are carried pivotally on a stud shaft 112 appropriately mounted in the framework (not shown) of the apparatus.

Slidably articulated to the stud shaft 12 and disposed midway between the blades 108 and 109 is a bar 113 which is pivotally connected at its lower end to an arm 114 pinned to a rock shaft 115. The depending arms 116 and 117, respectively of blades 108 and 109 are connected to the bar 113 by links 118 and 119, respectively, which in turn are pivotally connected to the bar 113 by a pivot stud 121 common to both links 118 and 119 to thus form a toggle mechanism. The rock shaft 115 oscillates continuously, thereby causing, through bar 113 and toggle links 118 and 119, the blades 108 and 109 to operate in scissor-like fashion.

In the operation of the selector according to the present invention, the signal impulses are received over line wire 47 to operate the magnet 11 accordingly. Since the normal stop condition of the line is marking (or current on the line) the magnet 11 is energized to hold its armature 12 in the solid line position shown in Fig. 3. In this condition the shoulder 21 of sensor 16 rests against the edge of the armature 12, and through projection 48, the stop bail 51 is effective to hold the disc 37, and hence the cam sleeve 26 against rotation, in well known manner in start-stop operation. In response to this stop condition the sensor 15 is also held away from the edge of armature 12 by its cam 17 thus permitting vibration of armature 12.

In response to a start condition of the line 47 (no current or spacing) the magnet 11 will become de-energized and its armature 12 will ride off the shoulder 21, thus permitting the sensor 16 to respond to the pull of its spring 24 (since its follower 59 is opposite a notch in cam 18). Since, in this condition, the cam follower portion of arm 49 is opposite notch 57 of cam 28, the bail 51 is permitted to respond to the pull of spring 122 to disengage extremity 54 from the stop lug 55 to release the disc 37 (and hence sleeve 26) for rotation to initiate start-stop operation.

In accordance with the present invention, only the sensors 15 and 16 cooperate with the armature 12, and none of the follower elements 41 to 45 cooperate directly with the armature 12. Instead, the follower elements cooperate with the

6

arms 64 carried by the sensor 15. The cams 31 to 35 are of similar cam contour but are displaced on the shaft 27 angularly so that the cam notches 133 are disposed in a helically arranged series whereby coaction with the cam follower portions 68 will occur in a sequential manner as the series of cams 31 to 35 rotates in synchronism with the speed of code impulsing. Thus, the cams 31 to 35 will sequentially allow the follower elements 41 to 45 to respond to the pull of their respective springs unless said elements are blocked through the coaction of the sensors and the armature 12.

The timing of the various cams is disclosed in Fig. 4. Line 123 represents the timing for the sensor control cam 17, while line 124 represents the timing for the sensor control and selector bail cam 18. It is noted that the contours of cams 17 and 18, as represented by lines 123 and 124, merge, and the apices 62 and the depressions 63 coincide, as also indicated in Fig. 3. It is also observed that the dotted line 124 (Fig. 4) is indicative of the cam notch 61 (Fig. 3). Lines 125 to 129 inclusive, represent the contours of the selector cams 31 to 35.

In the start or rest position of the cam assembly, exemplified by cam sleeve 26, the cam follower portions 68 of all of the selector levers 31 to 35 ride on the high portion or dwell of their associated cams. Soon after the signal cycle is initiated, the cam followers 68 simultaneously ride down their respective inclines 131 to the lower dwell portion 132 of the cams 31 to 35. Then, in timed relation with the receipt of the code impulses, the cam followers 68 will fall sequentially into the respective cam notches 133. For example, when the cam follower 68 of the first selector lever 31 falls into its associated notch 133, the lever 31 will rotate clockwise in response to the pull of its spring 67 to permit the end of the associated interponent or selectable element 72 to fall from shoulder 134 (where it normally rests) to the shoulder or step 73. Then, when the cam follower portion 68 cooperates with the incline 135 of the cam, the selector lever 31 is actuated counterclockwise, and since the interponent 72 is now engaging the step 73, the interponent 72 will be actuated leftwardly. Thus, operation of interponents 72 takes place pursuant to each received impulse, if the impulse is of marking nature, because in response to a marking impulse the magnet 11 will be held energized and the sensing lever or sensor 15 will be unblocked. In this condition, the lever 15 is permitted to follow the indent 63 of its cam 17, whereupon the lever 15 will move clockwise (Fig. 3) and arms 64 carried thereon will move rightwardly to permit the follower element 31 to move correspondingly.

If the signal impulse is of spacing nature, the armature 12 will be released (to assume its dotted line position in Fig. 3) and therefore will block the clockwise movement of the follower element 31, thereby preventing the interponent 72 from engaging shoulder 73, and thus the interponent 72 will remain unactuated. As indicated in the diagram shown in Fig. 4, the interponents 72, if actuated, will remain in their leftward or actuated position throughout the code cycle, since the cam follower portions 68 will ride on the dwell 136.

Line 137 represents the interponent reset cam 36. As seen in Fig. 1, the cam 36 has associated therewith a bail member 138 mounted pivotally on a shaft 139. The bail member 138 comprises

a cam follower portion 141 and a bail portion 142. As shown in Fig. 4, the cam 36 is provided with a projection 143 so located in relation to the selector cams 31 to 35 that the cam 36 is operative to lift the selected interponents 72 out of engagement with the shoulder 73 at substantially the same time that the cam follower portions 68 ride down the inclines 131. At the close of the selecting cycle (one revolution of sleeve 26) the selected interponents rest upon the shoulder or step 73, and so remain until immediately following the initiation of the next cycle, when the projection 143 acts to lift the interponents 72 out of engagement with shoulders 73, and substantially simultaneously the followers 68 of follower elements 41 to 45 ride down the cam slopes 131 and rest on the dwell 132 to maintain the interponents 72 upon surface 134 in readiness for the succeeding selective operation under the control of selector cams 31 to 35.

In said succeeding cycle, if the first code impulse is of marking nature, then the lever 15 will move clockwise, and accordingly the follower element 41 will follow the rod 64 (being permitted to do so by the depression 133 of cam 31) so that the end of interponent 72 will fall upon the step 73. Then, when the rise 135 of cam 31 acts upon follower 41 to actuate said follower 41 counterclockwise, the interponent 72 associated therewith will be actuated leftwardly (Fig. 1) where it (and the companion interponents that have been selected) will be held until the initial portion of the next cycle, when they will be stripped or reset by the reset bail 142.

An interponent 72 when actuated to its leftward position, will cooperate with arm 89 of transfer member 82 to move the transfer lever 82 to its counterclockwise position. Y-lever 92 will thus be swung, through the instrumentality of spring 97, to its clockwise position. The elements 99 and 100 of the operated Y-lever 92 will function to move bar 104 to bring the shoulder 107 in the path of the scissor bar 109, whereby the bar 104 will be moved leftwardly (as viewed in Fig. 1) pursuant to the oscillatory movement of the bar 109.

On the other hand, in response to a code signaling impulse of spacing nature, the interponent 72 will remain in its rightward position, and the transfer member 82 will remain against the stop 74. In this condition of operation the Y-lever 92 will assume its counterclockwise position so that, through its extremities 99 and 100, the bar 104 will be swung to its clockwise position to bring the shoulder 106 into the operating path of the scissor blade 108 whereupon the bar 104 will be actuated rightwardly.

Bars 101 to 105 are pivotally articulated to a corresponding series of permutation code bars 144 by means of disc and notch connections 145. The permutation code bars 144 are adapted to be detented by spring loaded detent means 146. Code bars 144 are analogous to code bars 62 to 66 disclosed in copending application Serial No. 22,653 filed April 22, 1948, by W. J. Zenner, which eventuated into U. S. Patent No. 2,505,729, dated April 25, 1950.

In Fig. 2 is shown a Y-lever 147, herein identified as the common Y-lever, since it is common to and responds to the operation of Y-levers 91 and 92. Y-lever 147 is provided with a laterally directed flange 148 adapted to span the Y-levers 91 and 92. A spring 149 connected to the Y-lever 147 normally biases the Y-lever 147 counterclockwise (as viewed in Fig. 2) to permit the flange

148 normally to bear against the Y-levers 91 and 92 common thereto. With this arrangement the common Y-lever 147 will be actuated clockwise whenever either one or both of the Y-levers 91 and 92 are actuated in response to signal impulses. Thus, when either Y-lever 91 or 92 are separately operated, or both are operated substantially simultaneously, the Y-lever 147 is also operated, whereupon the bar 151, similar to bars 102 and/or 104 will be actuated to present the shoulder 107 thereof into the path of scissor blade 109 to be actuated thereby. The function of the common Y-lever 147 is analogous to the common bar 67 disclosed in the aforementioned copending application.

Although only one embodiment of the invention has been disclosed hereinbefore, it will be understood that the invention is subject to many other modifications and adaptations, not disclosed herein, without departing from the scope thereof which is to be limited only by the appended claims.

What is claimed is:

1. In a telegraph apparatus, mechanism comprising cyclically operable cam means to control selective operations, signal responsive means including an armature for controlling said mechanism, a pair of armature sensing means included in said mechanism and controlled by said cam means, a plurality of selectors included in said mechanism, means carried by one of said armature sensing means and adapted to span said selectors to govern said selectors, and means controlled by the other of said armature sensing means to control the cyclic operation of said mechanism.

2. In a telegraph apparatus, mechanism comprising cyclically operable cam means to control selective operations, signal responsive means including an armature for controlling said mechanism, a pair of means included in said mechanism controlled by said cam means for sensing said armature, a plurality of selectors included in said mechanism, means carried by one of said armature sensing means and adapted to span said selectors for governing the response of said selectors to the movements of said one of said armature sensing means under the joint control of said cam means and said signal responsive means, and means controlled by the other of said armature sensing means to control the cyclic operation of said mechanism.

3. In a telegraph apparatus, cyclically operable cam means, instrumentalities associated with said cam means to control selective operations, signal responsive means including an armature, a pair of armature locking means controlled by said cam means for sensing said armature, means associated with certain of said armature locking means and adapted to span said instrumentalities to determine the effectiveness of said instrumentalities, and means controlled by other of said armature locking means to control the cyclic operation of said cam means.

4. In a telegraph apparatus, cyclically operable cam means, instrumentalities associated with said cam means to control selective operations, signal responsive means including an armature, plural means controlled by said cam means for sensing said armature, means associated with certain of said plural means to determine the effectiveness of said instrumentalities, means controlled by other of said plural means in response to a received signal to start said cam means into operation, and means for rendering

said start means non-responsive to a pre-determined number of subsequent signals.

5. In a telegraph apparatus, cyclically operable cam means, selectable elements associated with said cam means to control selective operations, signal responsive means including an armature, a pair of armature locking means controlled by said cam means for sensing said armature, means carried by one of said armature locking means to determine the effectiveness of said selectable elements, a plurality of actuators operably associated with said selectable elements, an instrumentality operably associated with each actuator, a member yieldably associated with each instrumentality, an element cooperably related to each member, a permutation bar associated with each element, operating means cooperable with said last recited elements as determined by said members according to the selective operation to selectively operate said permutation bar, and means controlled by the other of said armature locking means to control the cyclical operation of said cam means.

6. In a printing telegraph selector, a signal responsive means, a plurality of cams, a follower associated with each cam and urged to engage the surface thereof, said cams having low portions into which the followers are urged followed by raised portions for actuating the followers invariably, an actuator associated with each follower, an instrumentality associated with each actuator, a member yieldably associated with each instrumentality, an element cooperably related to each member, each of said elements having on opposite edges thereof oppositely disposed shoulder portions, a permutation bar associated with each element, and operating means cooperable with said shoulder portions as determined by said members according to the selective operation of said signal responsive means to selectively operate said permutation bar.

7. In a printing telegraph selector, a signal responsive means, a plurality of cams, a follower associated with each cam and urged to engage the surface thereof, said cams having low portions into which the followers are urged followed by raised portions for actuating the followers invariably, a slidable actuator associated with each follower, an instrumentality associated with each slidable actuator, a member yieldably associated with each instrumentality, an element cooperably related to said member, each of said elements having on opposite edges thereof oppositely disposed shoulder portions, a permutation bar associated with each element, and toggle operated means cooperable with said shoulder portions as determined by said members according to the selective operation of said signal responsive means to selectively operate said permutation bar.

8. In a printing telegraph selector, a signal responsive means, a plurality of cams, a follower associated with each cam and urged to engage the surface thereof, said cams having low portions into which the followers are urged followed by raised portions for actuating the followers invariably, a slidable actuator associated with each follower, an instrumentality associated with each slidable actuator, a stop, a member yieldably associated with each instrumentality by a single spring extended therebetween, said spring tending to maintain said instrumentality in a normal position against said stop, an element cooperably related to each member, a permutation bar associated with each element, and operating means cooperable with said element in one manner when

said instrumentality is in a normal position and in another manner when said instrumentality is operated to its off-normal position under control of said signal responsive means to correspondingly operate said permutation bars.

9. In a telegraph apparatus, mechanism controlled by received signals comprising cyclically operable cam means to control selective operations, signal responsive means including an armature, followers associated with said cam means and urged to engage the cam surfaces thereof, said cams having low portions into which the followers are urged followed by raised portions for actuating the followers invariably, a member associated with each follower for actuation thereby, a pair of armature locking levers included in said mechanism controlled by said cam means in synchronism with said received signals, and a pair of oppositely extending arms secured to one of said armature locking levers and adapted to cooperate with said followers, whereby the actuation of said followers toward said cams is controlled.

10. In a telegraph apparatus, mechanism comprising cyclically operable cam means to control selective operations, elements associated with said cam means and urged to engage the cam surfaces thereof, said cams having low portions into which said elements are urged followed by raised portions for actuating said elements, a member associated with each element for actuation thereby, signal responsive means including an armature for controlling said mechanism, a pair of armature locking means included in said mechanism controlled by said cam means, and control means associated with one of said armature locking means adapted to cooperate with said elements, whereby the actuation of said elements toward said cams is controlled by said control means.

11. In a telegraph apparatus, mechanism comprising cyclically operable cam means to control selective operations, signal responsive means including an armature for controlling said mechanism, a pair of armature locking means included in said mechanism controlled by said cam means, means associated with certain of said armature locking means to effectuate said selective operations, and means controlled by other of said armature locking means to control the cyclic operation of said mechanism.

12. In a telegraph apparatus, mechanism comprising cyclically operable cam means to control selective operations, signal responsive means including an armature for controlling said mechanism, a pair of armature locking means included in said mechanism controlled by said cam means, means associated with certain of said armature locking means to effectuate said selective operations, means controlled by other of said armature locking means operable in response to a received signal to start said cam means into operation, and means for rendering said start means non-responsive to a predetermined number of subsequent signals.

13. In a telegraph apparatus, mechanism comprising cyclically operable cam means to control selective operations, followers associated with said cam means and urged to engage the cam surfaces thereof, said cams having low portions into which the followers are urged followed by raised portions for actuating the followers, a slidable actuator associated with each follower for actuation thereby, signal responsive means including an armature for controlling said

mechanism, armature locking means included in said mechanism controlled by said cam means, means associated with certain of said armature locking means adapted to cooperate with said followers, whereby the actuation of said followers toward said cams is controlled, and means controlled by other of said armature locking means to control the cyclic operation of said mechanism.

14. In a telegraph apparatus, mechanism comprising cyclically operable cam means to control selective operations, followers associated with said cam means and urged to engage the cam surfaces thereof, said cams having low portions into which the followers are urged followed by raised portions for actuating the followers, a 5 slidable actuator associated with each follower for actuation thereby, signal responsive means including an armature for controlling said mechanism, armature locking means included in said mechanism controlled by said cam means, means associated with certain of said armature locking means adapted to cooperate with said followers, whereby the actuation of said followers toward said cams is controlled, means controlled by other of said armature locking means operable in response to a received signal to start said cam means, and means for rendering said start means non-responsive to a predetermined 10 number of subsequent signals.

15. In a telegraph apparatus, mechanism controlled by received signals comprising cyclically operable cam means to control selective operations, a plurality of slidable actuators associated with said cam means, a pivoted instrumentality associated with each slidable actuator, a pivoted Y-lever yieldably associated with each instrumentality, a push-pull element operably disposed between the bifurcations of each Y-lever, each of 15 said elements provided on opposite edges thereof with oppositely directed offsets, a permutation bar associated with each element, and a scissors-type operator cooperable with said offsets as determined by said Y-levers according to the selective operation of said mechanism to selectively operate said permutation bars.

16. In a telegraph apparatus, mechanism controlled by received signals comprising cyclically operable cam means to control selective operations, a plurality of slidable actuators associated with said cam means, an instrumentality associated with each slidable actuator, a bifurcated member yieldably associated with each instrumentality, an element operably disposed between the bifurcations of each member, a permutation bar associated with each element, and operating means cooperable with said elements as determined by said bifurcated members according to the selective operation to selectively operate said permutation bar.

17. In a telegraph apparatus, mechanism controlled by received signals comprising cyclically operable cam means to control selective operations, a plurality of slidable actuators associated with said cam means, an instrumentality associated with each slidable actuator, a bifurcated member yieldably associated with each instrumentality, a shouldered element cooperably disposed between the bifurcations of each member, a permutation bar associated with each element, and operating means cooperable with the shoulders of said elements as determined by said bifurcated members according to the selective operation to selectively operate said permutation bar.

18. In a printing telegraph selector, a plurality of cams, a follower associated with each cam and urged to engage the surface thereof, said cams having low portions into which the followers are urged followed by raised portions for actuating the followers invariably, a slidable actuator associated with each follower for actuation thereby, a signal responsive means including an armature and a pair of locking levers having oppositely disposed stepped extremities cooperable with the extremity of said armature, said armature adapted to cooperate solely with said locking levers, and a pair of oppositely extending arms secured to one of said locking levers and adapted to cooperate with said followers whereby the actuation of said followers toward said cam is controlled.

19. In a printing telegraph selector, the combination of a plurality of cams, a follower associated with each cam and urged to engage the surface thereof, said cams having low portions into which the followers are urged followed by raised portions for actuating the followers invariably, a slidable actuator associated with each follower, and a signal responsive means including an armature and a pair of locking levers, characterized in this that said armature cooperates solely with the pair of locking levers, and one of said locking levers is provided with means adapted to cooperate with said followers to control the actuation of said followers toward said cams.

20. In a printing telegraph selector, the combination of a plurality of cams, a follower associated with each cam and urged to engage the surface thereof, said cams having low portions into which the followers are urged followed by raised portions for actuating the followers invariably, a slidable actuator associated with each follower, and a signal responsive means including an armature, characterized in this that a pair of locking levers having shouldered extremities cooperates with the extremity of the armature, said armature adapted to cooperate solely with said locking levers, and a pair of oppositely extending arms secured to one of said locking levers and adapted to cooperate with said followers to control the actuation of said followers toward said cams.

21. In a printing telegraph selector, a signal responsive means including a plurality of cams, a follower associated with each cam and urged to engage the surface thereof, said cams having low portions into which the followers are urged followed by raised portions for actuating the followers invariably, a slidable actuator associated with each follower, a pivoted instrumentality associated with each slidable actuator, a pivoted Y-lever yieldably associated with each instrumentality, a push-pull element operably disposed between the bifurcations of each Y-lever, each of said elements provided on opposite edges thereof with oppositely directed offsets, and a permutation bar associated with each element, and a scissors-type operator cooperable with said offsets, as determined by said Y-levers according to the selective operation of said signal responsive means to selectively operate said permutation bars.

22. In a printing telegraph selector, a signal responsive means, a plurality of cams, a follower associated with each cam and urged to engage the surface thereof, said cams having low portions into which the followers are urged followed by raised portions for actuating the followers in-

variably, a slidable actuator associated with each follower, a pivoted instrumentality associated with each slidable actuator, a pivoted Y-lever yieldably associated with each instrumentality, a push-pull element operably disposed between the bifurcations of each Y-lever, a permutation bar associated with each element, and operating means cooperable with said elements as determined by said Y-levers according to the selective operation of said signal responsive means to selectively operate said permutation bars.

23. In a printing telegraph selector, a plurality of cams, a follower associated with each cam and urged to engage the surface thereof, said cams having low portions into which the followers are urged followed by raised portions for actuating the followers invariably, a slidable actuator associated with each follower for actuation thereby, a signal responsive means including an armature and a pair of locking levers having oppositely disposed stepped extremities cooperable with the extremity of said armature, said armature adapted to cooperate solely with said locking levers, a pair of oppositely extending arms secured to one of said locking levers and adapted to cooperate with said followers to control the actuation of said followers toward said cams, a pivoted instrumentality associated with each slidable actuator, a pivoted Y-lever yieldably associated with each instrumentality, a push-pull element operably disposed between the bifurcations of each Y-lever, each of said elements provided on opposite edges thereof with oppositely directed offsets, a permutation bar associated with each element, and a scissors-type operator cooperable with said offsets as determined by said Y-levers according to the selective operation of said signal responsive means to selectively operate said permutation bars.

24. In a printing telegraph selector, a signal responsive means, a plurality of cams, a follower associated with each cam and urged to engage the surface thereof, said cams having low portions into which the followers are urged followed by raised portions for actuating the followers invariably, a slidable actuator associated with each follower, a pivoted instrumentality associated with each slidable actuator, a pivoted Y-lever yieldably associated with each instrumentality, an element operably disposed between the bifurcations of each Y-lever, a permutation bar associated with each element, and operating means cooperable with said elements as determined by said Y-levers according to the selective operation of said signal responsive means to selectively operate said permutation bars.

25. In a printing telegraph selector, a signal responsive means, a plurality of cams, a follower associated with each cam and urged to engage the surface thereof, said cams having low portions into which the followers are urged followed by raised portions for actuating the followers invariably, a slidable actuator associated with each follower, an instrumentality associated with each

slidable actuator, a bifurcated member yieldably associated with each instrumentality, an element operably disposed between the bifurcations of each member, a permutation bar associated with each element, and operating means cooperable with said elements as determined by said bifurcated members according to the selective operation of said signal responsive means to selectively operate said permutation bar.

26. In a telegraph apparatus, mechanism controlled by received signals comprising cyclically operable cam means to control selective operations, signal responsive means including an armature, elements associated with said cam means and urged to engage the cam surfaces thereof, said cams having low portions into which the elements are urged followed by raised portions for positively actuating the elements invariably, a member associated with each element for positive actuation thereby, a pair of means controlled by said cam means for sensing said armature, means carried by one of said armature sensing means and adapted to span said elements, whereby the actuation of said elements toward said cams is controlled, and means controlled by the other of said pair of means to control the cyclical operation of said cam means.

27. In a telegraph apparatus, mechanism controlled by received signals comprising cyclically operable cam means to control selective operations, signal responsive means including an armature, followers associated with said cam means and urged to engage the cam surfaces thereof, said cams having low portions into which the followers are urged followed by raised portions for actuating the followers invariably, a member associated with each follower for actuation thereby, a pair of armature locking levers included in said mechanism controlled by said cam means in synchronism with said received signals, and laterally directed means secured to one of said armature locking levers and adapted to cooperate with said followers, whereby the actuation of said followers toward said cams is controlled.

WALTER J. ZENNER.
